UNITED STATES PATENT OFFICE.

HYMAN MAIMIN AND AUGUST FREDDY, OF NEW YORK, N. Y., ASSIGNEES TO H. MAIMIN CO., INC., A CORPORATION OF NEW YORK.

CLOTH-CUTTING MACHINE.

Application filed January 4, 1922. Serial No. 526,872.

To all whom it may concern:

Be it known that we, HYMAN MAIMIN and AUGUST FREDDY, citizens of the United States of America, residing at New York, 5 county and State of New York, and whose post-office address is 251 West 19th Street, New York city, New York, have invented certain new and useful Improvements in Cloth-Cutting Machines; and we do hereby 10 declare the following to be a full, clear, and exact description of the invention, such as will enable others skilled in the art to which it appertains to make and use the same.

Our invention is an improvement in cloth-cutting machines and relates particularly to machines of the rotary type.

In machines of this character, the rotary knife or blade requires frequent grinding, and abrasive wheels or stones are commonly 20 provided, pivotally mounted on the machine, to be swung at will into and out of operative position, with respect to the blade. Means are usually provided near the handle, for enabling the operator to move the 25 abrasive wheels into operative position, without releasing his grasp of the handle. The most satisfactory results in sharpening are obtained when the abrasive wheels engage the rotary knife or blade at about the 30 level of the center. The guard for the front of the blade should be arranged as near to the edge of the blade as is practical, for obvious reasons, and when so arranged, it is not practicable to so arrange the abrasive 35 wheels that they will engage the blade near the level of the center, without interfering with the guard. To obviate this difficulty, such wheels have been arranged in front of the guard, that is with the guard between 40 the abrasive wheels and the blade. When so mounted, however, it is necessary to move the guard out of position between the abrasive wheels and the blade, before the abrasive 45 wheels can engage the blade.

It is an object of the present invention to design, in connection with cloth-cutting machines of this type, improved means for moving the abrasive wheels into and out of operative position and for moving the guard 50 out of and into operative position at the same time.

In order that the guard be held firmly in position, locking means should be provided, and these must be released as the abrasive 55 wheels are moved into sharpening position.

If the locking means are released the moment the wheels start toward the blade, and if the guard starts to swing out of its operative position simultaneously with the movement of the wheels toward the blade, the blade is 60 left unguarded for a time. In accordance with the present invention, when the operator swings the abrasive wheels toward the blade, this movement starts to release the locking mechanism, but this release is not 65 completed until the wheels have been swung down in front of the blade, and are just about to make contact therewith. When this point is reached, the lock is entirely 70 released, the guard is swung out of operative position, and the wheels are moved into contact with the blade. In this way, the blade is always protected either by the guard itself or by the wheels. We also provide a simple adjusting mechanism for the 75 guard, for enabling it to be adjusted vertically, to any desired position. We furthermore provide a new and improved mounting for the abrasive wheels, so arranged as to provide a double or two-point bearing for 80 each wheel, each bearing being beyond the plane of the wheel.

In the accompanying drawings, which disclose a preferred embodiment of our invention, —

Figure 1 is a side view of a cloth-cutting machine equipped with guard and abrasive wheels operated in accordance with the present invention,

Figure 2 is a view of the abrasive wheels 90 and guard, looking at the opposite side from Figure 1,

Figure 3 is a front view of the rotary blade,

Figure 4 is a plan view with the motor 95 removed, and the motor shaft in cross section,

Figure 5 is a horizontal section through the mounting for the abrasive wheels,

Figure 6 is a horizontal section at the 100 locking pin.

In the present embodiment of the invention, the improved machine comprises a base 1, having a standard 2, carrying a support 3 at its top for the motor 4, and the cutting blade 5 is journaled on the standard, being connected to the shaft of the motor 4, to be driven thereby. A handle 6 extends rearwardly from the standard, and by means of this the machine may be manipulated. This 110

is the usual construction of machine, and a guard 7 is provided in connection with the standard, and forming a part thereof, for the rear of the blade.

5 The guard 8 for the front of the blade, is in the form of a rod, having a knurled head 9 at its upper end, for convenience in manipulating the same, and the guard is adjustably held in a bracket 10, which is pivoted 10 to a lug 11 extending forwardly from the standard, at about the level of the handle 6. A headed pin 11^a is mounted to move laterally in an opening in the bracket 10. The pin has a flange 12 at its inner end, which is arranged to engage one face of the guard 8, when the pin is in its outermost position, and which is normally held in this position by a spring 13 which encircles the pin between the head and the bracket. It will be 15 evident that when the pin is pressed inwardly, the flange 12 will release the guard, and the guard may be adjusted vertically. The bracket 10 has a forked extension 14 at its inner side, and the arms of the fork are 20 adapted to engage a stop 15 on the lug 11, to limit the swinging movement of the bracket in either direction. Referring to Figure 4, it will be seen that the guard 8 is lateral to the plane of the cutting blade, and 25 the bracket 10 is so arranged that the guard is held sufficiently far in front of the cutting blade to protect the operator against injury, and it is normally held in this position, by means of a spring 16 encircling the pivot 17 of the bracket, and engaging at one end the stop 15 before mentioned. The other end of the spring engages the bracket. The bracket 10 is pivotally connected by a pivot pin 17, which also supports a double yoke 18. The 30 yoke has arms 19 engaging opposite sides of the lug 11 before mentioned, and pivoted thereto by the pin 17, which supports the bracket 10. The yoke also has arms 21—21^a which carry the abrasive wheels to be described, and the yoke is mounted to be swung vertically toward and from the cutting blade, by means of a trigger 22 pivoted to the handle as indicated at 23. The pivot pin 17 of the yoke carries a gear segment 24, meshing with a segment 25 pivoted on the standard, and the segment 25 is connected to the trigger by means of a link 26. When the trigger 22 is swung toward the handle 6, the gear segment 24 is swung on its pivotal mounting, and partially rotates the segment 24, which swings the yoke 18. A spring 26^a is provided for returning the parts to normal position, the spring being arranged between the trigger and the standard.

35 In common practice, the abrasive wheels used for sharpening the knives in cutters of this type are carried by a yoke and each wheel supported, either by a single stub shaft journaled in one arm of the yoke, or mounted upon a common shaft extending between and

40 journaled in the yoke arms, one of the wheels being fixed to this shaft, and the other loosely journaled upon it. Neither of these arrangements is satisfactory because the wheels are not rigidly journaled, and after 45 a time they work loose in their bearing so that they do not act efficiently, but on the contrary, are likely to impair the cutting edge of the knife. In accordance with the present invention, we have provided a simple double or two-point bearing for each abrasive wheel, which acts very effectively to prevent the loosening described above, and which therefore keeps the wheels in true 50 sharpening condition for a much longer time than is possible when using the other types of bearing supports. As shown in the drawings, the abrasive wheels 27 are supported by the arms 21 of the yoke. Each of these 55 wheels is counter-bored on its inner face as shown at 28, and each wheel has an axial bushing 29, extending from the bottom of the counter-bore beyond the outer face of the wheel. Locking rings 30 are threaded onto each bushing at the outer face of the wheel, and each bushing has a reduced portion 31, acting as a stub shaft, journaled engaging within a chambered screw 32 having threaded engagement with the adjacent arm 21 of the yoke. The screws 32 are in alignment, and the wheels are thus rotatably journaled in the screws. A shaft 33 is journaled within the bushings, the shaft extending across the space between the adjacent ends 60 of the bushings, and to near the outer ends of the bushings, being however spaced from the said ends as clearly shown in Figure 5. Washers 34 encircle the shaft within the counter-bores 28 of the wheels, and a coil spring 35 arranged between the washers, the spring normally holding the wheels against the locking rings 30. The arms 21—21^a are split as shown, the chambered 65 screws 32 being held between the split portions thereof. By loosening screws 37 which connect the sections of the arms, the screws 32 are released so that they may be adjusted, and they are locked in adjusted position by means of the screws 37. By thus mounting the abrasive wheels, each wheel has two 70 bearings, each situated beyond its own plane. One of these bearings is that of the reduced portion of the bushing or stub shaft 31 in the chambered screw 32, and the other is that of the shaft 33 in the bushing 29 of the other wheel. This arrangement makes for a rigid support so that the wheels are not likely to 75 work loose in their bearings.

77 Referring to Figure 3, it will be seen that the arm 21 of the yoke 18 extends in front of the guard 8, and is in position to engage the guard below the bracket 10, when the abrasive wheels are swung downwardly into grinding position, and to swing the guard in beyond the edge of the cutting blade, into 80

a position where it will not interfere with the operation of the said wheels. Thus when the abrasive wheels are swung into operative position, the guard is moved inwardly, and when the abrasive wheels swing into inoperative position, the spring 16 moves the guard back into normal position.

It is necessary, however, that the guard be locked in such position, otherwise it would swing inwardly when engaged by the hand of the operator, for instance, permitting the hand to strike the cutting blade. It is also essential that the locking means be automatically released when the abrasive wheels are swung toward operative position, and just before the arm 21 of the yoke engages the guard. For locking the guard in operative position, we provide a locking pin 37^a, which is mounted to slide in an opening 20 in the lug 11 before mentioned, toward and from the forked extension 14 of the bracket 10. This extension has an opening 38 for engagement by the pin, and the pin is normally pressed toward the opening by a 25 spring 39, which is arranged between the lug 11 and a flange or rib 40 on the pin. When the guard is in normal position, the spring 40 presses the pin into engagement with the opening 38 of the fork extension, 30 and mechanism is provided on one of the arms 19 of the yoke for releasing the pin. Such mechanism is in the form of a cam extension 41, which is adapted to engage beneath the head of the pin 37^a, and referring 35 to Figure 4, it will be seen that the face of the head adjacent to the pin is bevelled to cooperate with the cam extension. When the yoke 18 is swung downwardly toward operative position, and just before the arm 40 21 engages the guard, the cam extension releases the pin 37^a, which releases the bracket 10, so that as the arm 21 of the yoke engages the same, the guard is free to move inwardly 45 to inoperative position, where it will not interfere with the operation of the cutting blade.

We claim—

1. In a cloth-cutting machine, the combination of a cutting blade, a guard therefor arranged laterally with respect to the plane of the blade and mounted to swing into inoperative position alongside the blade, sharpening means mounted to move into grinding contact with the blade and having means for engaging the guard to move the same into inoperative position, normally operative means for locking the guard in operative position, said locking means being released during the first part of the movement of the sharpening means toward the blade.

2. In a cloth-cutting machine, the combination of a cutting blade, a guard therefor arranged laterally with respect to the plane 65 of the blade and mounted to swing into in-

operative position alongside the blade, sharpening means mounted to move into grinding contact with the blade and having means for engaging the guard to move the same into inoperative position, a spring 70 pressed locking pin for engaging the guard to hold it in operative position, and a cam carried by the sharpening means for engaging the pin to release the same.

3. In a cloth-cutting machine, the combination with the frame and the rotary blade, of a guard for the blade pivotally movable with respect to the frame, a pin mounted to slide in the frame transversely of the guard and having means for engaging the same to hold it from pivotal movement, and a spring 80 pressing the pin toward the guard.

4. In a cloth-cutting machine, the combination of a blade, a guard therefor, locking means holding the guard in operative position, sharpening means for the blade, means for moving the sharpening means into contact with the blade, means for releasing the locking means just before the sharpening 85 means contact with the blade, and means for moving the guard out of operative position when the locking means are released.

5. In a cloth-cutting machine, the combination of a cutting blade, a guard therefor arranged laterally with respect to the plane 90 of the blade and mounted to swing out of inoperative position alongside the blade, normally operative means for locking the guard in operative position, sharpening means mounted to swing into grinding contact with the blade, and having means for engaging the guard to move the same into inoperative position, and means for releasing the locking means during the first 95 part of the swinging movement of the sharpening means toward the blade, said locking means being completely released when the sharpening means engage the guard.

6. In a cloth-cutting machine, the combination of a rotary blade, a guard therefor, pivoted to swing in a plane parallel to the plane of the blade into and out of operative position, abrasive wheels carried by a yoke 115 pivoted to swing into and out of operative relation to the blade, normally operative means for locking the guard in operative position, means carried by the yoke for releasing the locking means during the first part of the movement of the abrasive wheels toward the blade, the release of the locking means being complete when the yoke contacts with the guard; whereby further movement of the wheels toward the blade swings 120 the guard out of operative position.

In testimony whereof we affix our signatures.

HYMAN MAIMIN.
AUGUST FREDDY.
